(57) **CLAIM**

The ornamental design for a train set, as shown and described.

DESCRIPTION

FIG. 1 is a top, rear perspective view of a train set showing my new design;

FIG. 2 is a top, front perspective view thereof;

FIG. 3 is a bottom, front perspective view thereof;

FIG. 4 is a bottom, rear perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The broken lines in the FIG. 9 depict the portions of the article that form no part of the claimed design.
